George Augustus Scott Inventor

By his Attorney G. J. Gordon.

UNITED STATES PATENT OFFICE.

GEORGE A. SCOTT, OF NEW YORK, N. Y.

DESIGN FOR A CURLING AND CRIMPING COMB.

SPECIFICATION forming part of Design No. 18,926, dated February 12, 1889.

Application filed December 11, 1888. Serial No. 293,302. Term of patent 7 years.

To all whom it may concern:

Be it known that I, GEORGE AUGUSTUS SCOTT, a citizen of the United States, residing in the city of New York, county and State of New York, have invented and produced a new and original Design for Curling and Crimping Combs, of which the following is a specification, reference being had to the accompanying drawings, forming part thereof.

10 Figure 1 is a side elevation of my newly-designed crimper; Fig. 2, a sectional view at the line x x of Fig. 1, and Fig. 3 a sectional view at the line y y of Fig. 1.

The main characteristic of my design is found in the outlines of the comb-section of the device. It is round at the shank and of plain shape, extending straight and nearly

flat to its extreme end, presenting a thin back and flat tapering sides, in which the teeth are cut. The handle corresponds in circumference and shape with the shank of the comb part at their point of junction. 20

What I claim as my invention is—

A design for a curling and crimping comb, exhibiting a round shank, but flat-sided and tapering to the points of the teeth and nearly flat on the back, with a round handle having a depression a little above its junction with the shank, substantially as shown.

GEO. A. SCOTT.
